S. PAUL

JERK ABSORBER

Filed Feb. 26, 1925

Inventor;

Sydney Paul;

Robert W. Sandell,

Attorney.

UNITED STATES PATENT OFFICE.

SYDNEY PAUL, OF LIMA, OHIO, ASSIGNOR TO THE SUPERIOR MOTOR COACH BODY COMPANY, OF LIMA, OHIO, A CORPORATION OF OHIO.

JERK ABSORBER.

Application filed February 26, 1925. Serial No. 11,749.

To all whom it may concern:

Be it known that I, SYDNEY PAUL, a citizen of the United States, residing in the city of Lima, county of Allen, State of Ohio, have invented a new and useful Jerk Absorber, of which the following is a full, clear, and comprehensive specification and exposition, being such as will enable others to make and install the same with exactitude.

The object of this present invention is to provide means to absorb sudden jerks or pulls, as quick starts in the operation of motor vehicles, whereby the transmission of such jerks to a person seated in the vehicle will be minimized.

This invention contemplates the use of chairs or the like in connection with commercial passenger-vehicles, such for instance as that shown by me in applications Serial No. 5932 and No. 5933, both filed January 31, 1925, and now pending in the Patent Office; and in Design Patent No. 66,980, dated April 7, 1925.

Other objects and particular advantages of the invention will suggest themselves in the course of the following description, and that which is new will be correlated in the appended claim.

One manner of carrying out the principles of my invention in a practical and efficient way is shown in the accompanying drawings, in which—Figure 1 shows a pair of my devices in connection with the lower portion of a chair with which they are connected. Figure 2 is a perspective view of the casing alone of one of the devices. Figure 3 is a perspective view of the piston-rod and head alone. Figure 4 shows the spring alone. And Figure 5 is a vertical central section taken through one of the devices.

Similar indices denote like parts throughout the several views.

In order that the construction, the operation, and the advantages of my invention may be more fully understood and appreciated, I will now take up a detailed description thereof.

In the drawings letter A denotes the base or body of a chair which carries the seat or cushion B. Letters C and D denote the in-turned feet of the front legs of the chair;

and letters E and F denote the feet of the rear legs. Letter G denotes the floor of the vehicle in which my invention is to be installed.

As the two devices required for each chair are identical with each other I will describe but one and the same parts of the other will be denoted by like character, where shown.

Each of the jerk-absorbers comprises a casing 1 having four sides and a top all integral with each other. The lower end of the casing, which is open, is formed at an angle with relation to the other parts, whereby when placed on a level surface it will stand at an inclination, as is shown in the drawings.

The lower portions of two of the adjoining sides of the casing are cut-away forming a notch 2, as is clearly indicated.

Extending out horizontally from the lower edges of the two sides which are not cut-away is the flange 3, which is adapted to rest flat upon the floor G where it is adapted to be secured by a plurality of bolts 4, or otherwise.

At this point it should be understood that two of the devices are to be secured to the floor G, with the horizontal end portions of the feet C and D projecting thereinto, that is into the notches 2, but at the same time they rest on the floor G, as shown in Fig. 1. When secured in position as in Fig. 1 the two devices will lean rearward at substantially the inclination shown in Fig. 5.

Formed integral with and extending down into the interior of the casing from the top thereof, and concentric therewith, is the tubular guide 5. Numeral 6 denotes the piston-rod, which is adapted to fit slidably in the tubular guide 5, extending thereabove and below.

Numeral 7 denotes a packing gland formed on the surface of the top of the casing, concentric with the aperture in the guide 5.

Said gland is to be packed with an absorbent material filled with lubricant, in order to lubricate the rod 6 and the wall of the interior of the guide 5.

Numeral 8 denotes the plunger-head, which is rigidly secured on the lower end of the rod 6, and it is adapted to be moved up and down in the casing between the floor G

and the lower end of the guide 5. The underface of the head 8 is formed concave or notched, as shown at 9 in Fig. 5, in order to engage over the end of the front leg C, or D, of the chair.

Formed in one edge of the head 8 is a channel 11. A rib 12 is formed integral with one side of the inner wall of the casing 1, which rib is adapted to fit in the channel 11, in order to prevent the head 8 from turning, that is forming a guide therefor. Numeral 10 denotes a helical-spring which surrounds the guide 5, with one end in contact with the under-side of the top of the casing, and the other end in contact with the top of the head 8.

An aperture 13 is formed through the upper portion of the rod 6 to receive the pin 14. When the device is not in use, or when 20 it is desired to release the feet C and D, then the rod 6 can be drawn upward, against the resiliency of the spring 10, where it may be secured by the pin 14 to be inserted in the aperture 13.

25 It will now be seen that if two of the devices be secured to a floor, as in Fig. 1, with the feet C and D placed therein, and the heads 8 resting on said feet, the pin 14 being removed, that if the vehicle carrying the floor G and said chair, that if the vehicle be given a jerk forward that the weight of the person seated in the chair will cause the chair to incline to tip backward, which will raise the feet of the chair from the floor, but 30 on account of the resiliency of the springs 10 this backward tipping of the chair will be absorbed by the springs, that is permitting the chair to tip sufficient to absorb the shock and then the springs will return the

feet of the chair to the floor, thereby accomplishing the objects of the invention. 40

It will also be seen that said devices also act as pivots to permit the chair to be turned forward for the purpose of cleaning the floor under the chair, and for various other purposes. 45

It is apparent that by pulling upward on the rods 6 and then returning them upward by inserting the pin 14 in its apertures 13, that first one and then the other of said feet 50 may be removed by springing them outward and forward or rearward.

I desire that it be understood that various changes may be made in the several detail herein set forth without departing from the spirit of the invention and without sacrificing any of the advantages thereof which are new and useful. 55

Having now fully shown and described my invention, what I claim and desire to secure by Letters Patent of the United States, is— 60

A jerk absorber comprising a casing having a top and an open lower end with an aperture through the center of the top, there being a notch formed in the lower end portion of the casing, means for securing the lower end of the casing to a floor, a tubular guide extending from the center of the top down into the interior of the casing, a rod 65 slidable in said guide and extending therebelow and through said aperture in the top of the casing, a head secured to the lower end of said rod and operative up and down in the casing, and a coil spring surrounding 70 said guide and engaging the head. 75

SYDNEY PAUL.
